CLAIM

The ornamental design for a holder for smoker's pipe and accessories, as shown and described.

DESCRIPTION

FIG. 1 is a perspective view of a holder for a smoker's pipe and accessories showing my new design;

FIG. 2 is a top plan view thereof;

FIG. 3 is a bottom plan view thereof;

FIG. 4 is a side elevational view thereof, the opposite side elevational view being identical; and,

FIG. 5 is an end elevational view thereof; the opposite end elevational view being identical.

FIG. 1

FIG. 2

FIG. 3

FIG. 4

FIG. 5
